STRIP DOUBLER FOR STRIP MILLS

Howard C. Poole, Newton Falls, and Harry W. Moseley, Warren, Ohio; said Moseley assignor of one-fourth to said Poole

Application January 26, 1935, Serial No. 3,536

10 Claims. (Cl. 153—21)

This invention relates to strip mills.

The principal object of this invention is to provide a device for doubling a strip of material over on itself during the process of reducing the same in order to produce relatively light gauge strips from metal or other material.

A further object of this invention is to provide a device for the purpose of doubling a strip of material upon itself in the process of reducing the strip in order to produce two layers or other multiples of two layers, depending upon the number of times doubled.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention is illustrated in the accompanying drawings, wherein:—

Figure 1 is a side elevation of certain elements of the apparatus in the position they occupy immediately preceding the doubling operation;

Figure 1a a view similar to Figure 1 showing certain elements of the apparatus in the position they would occupy just before the completion of a doubling operation.

Figure 2 is a side elevation of a plurality of rolling mills carrying the doubled strip after leaving the device shown in Figure 1.

Figure 3 is a side elevation of a unit of the device showing the shearing of the doubled end, the separation of the layers, and the heating furnace.

Figures 4 and 4a are views similar to Figures 1 and 1a respectively, showing a two layer strip being operated upon.

Figure 5 is a side elevation of a plurality of rolling mills, similar to the mills illustrated in Figure 2, but now rolling the strip, four layers in thickness, and also showing a shearing device for cutting the doubled end through the four layers.

Figure 6 is a side elevation of a unit of the device showing the structure for separating the strips and winding on reels.

Figure 7 shows a cross section taken from a plan view of the first portion of Figure 1, the section being on the center line of the roller table.

Figure 8 is a cross section taken from a plan view of a part of Figure 1, the section being on the center line of the roller table, showing a

continuation of the movement started in Figure 7.

Figure 9 is a cross section taken from a plan view of a part of Figure 1, the section being on the center line of the roller table, showing an advanced movement from that shown in Figure 8.

Figure 10 is a cross section taken on line 10—10 of Figure 1.

Figure 11 is a detail view of a portion of Figure 10, showing a view of a quarter angle from that shown in Figure 10.

Figure 12 is a cross section taken on line 12—12 of Figure 1a.

Figure 13 is a side elevation of a portion of the left end of Figure 1 showing advanced movement of the strip and movable parts.

Figure 14 is a side elevation of a portion of the left end of Figure 1 showing a continued movement from that shown in Figure 13.

Figure 15 is a side elevation of a portion of the left end of Figure 1 showing a continued movement from that shown in Figure 14.

Figure 16 is a side elevation showing an advanced movement of parts and strip over that shown in Figures 13, 14, and 15.

It will be seen by referring to Figure 1 that the advance end of a strip 1, after having passed through the rolls of a mill 2, then passes under a roller 3 which is supported above a table roller 4 by supporting arms 5 which are part of a trolley 6. This trolley 6 is carried on wheels which roll on a track of structural members 7 supported above a roller table 8 by columns placed at intervals alongside of the roller table 8. The moving of this trolley 6 is accomplished by connecting the trolley wheels with a sprocket chain to the electric motor 9 or, if preferred, the trolley 6 can be moved by a chain driven from a stationary motor suitably located.

Referring also now to Figure 10 together with Figure 1, the advancing end of the strip 1 next enters gripper jaws 10, composed of a stationary jaw 11 and a movable jaw 12. Immediately after the advancing end of the strip 1 passes the gripper jaws 10 it comes in contact with an electrical trigger switch 13. A lever 14 of this switch 13 is pushed down by the end of the strip 1, which then rolls on over a wheel 15 on the lever 14. The pushing down of this wheel 15 makes an electrical contact within the switch 13 which allows an electrical current to flow into a reversing type motor 16, mounted on the track 7 above the gripper jaws 10. The motor 16 is set in motion, and this rotary motion is

transmitted to a sprocket wheel 17 on the motor's shaft, and thence to a sprocket chain 18, which runs over a second sprocket wheel 19. This sprocket wheel 19 is mounted on one end of a solid shaft 20. Thus the rotary motion of the motor shaft is transmitted to the solid shaft 20. By referring to Figures 7, 8, 9, and 10 it will be seen that the solid shaft 20 revolves in a hollow shaft 21. This hollow shaft 21 has a part 10 of the wall cut out about midway of its length. In the opening thus made is located a cam 22 which is fastened rigidly to the solid shaft 20. The rotary motion of the solid shaft 20 is thus transmitted to the cam 22. Part of the cam surface 15 rests on one end of the movable jaw 12. This movable jaw 12 reciprocates in guides 23 and has a spiral spring 24 around it which forces it against the cam 22. The rotary motion of the cam 22 forces the movable jaw 12 down against the strip 1 thus forcing the strip 1 against the stationary jaw 11. The strip 1 is now held tightly between the stationary jaw 11 and the movable jaw 12. No further downward movement 20 of the movable jaw 12 is possible because the stationary jaw 11 is supported at its ends by arms 25 which are in turn fastened rigidly to the hollow shaft 21. Therefore, since the motor 16 is still revolving, the motion is transmitted 25 through this train of parts to the hollow shaft 21 which now starts to revolve in bearings 26 which are supported from the track 7 above by arms 27. On one end of the hollow shaft 21 is rigidly fastened a sheave 28. The sprocket wheel 19, solid shaft 20, cam 22, movable jaw 12, stationary jaw 11, arms 25, hollow shaft 21, and sheave 28 now revolve together about a common center.

Since the advance end of the strip 1 is gripped 40 tightly in gripper jaws 10, this advanced end is carried along with the revolving of above named parts. By referring to Figure 8 it will be seen that this movement is taking place. As the sheave 28 revolves it wraps around itself a cable 45 29, which passes over idler sheaves 30 which are shown in Figure 10. This cable 29 is fastened to a counterweight 31. As the cable 29 is wrapped around the sheave 28 this counterweight 31 is raised in a safety guard 32.

50 By referring to Figures 7, 8, 9, and 10 it will be seen that there is a second electrical trigger switch 33 mounted on the inside of one of the arms 27. The trigger of this switch 33 is tripped by a finger 34 fastened rigidly to the hollow shaft 21. When the motor 16 revolves the hollow shaft 21, this finger 34 trips the trigger switch 33 and sends an electrical current to the motor 9 on the trolley 6. The trolley 6 at once starts to move away from the mill, carrying with 55 it the roller 3. This roller 3 is carried under the gripper jaws 10 as shown in Figure 8, the gripper jaws 10 having revolved to the position shown. The revolving of the gripper jaws 10 is continued until they reach a position as shown 60 in Figure 9. By referring to Figure 10 it will be seen that there is indicated a cam 35 of an electrical rotary switch mounted on the hollow shaft 21 and revolves with it. At this position of the movement, as indicated in Figure 9, the cam 35 runs off a contact shoe 36 and the current is disconnected from the motor 16. The disconnecting of this current automatically sets a solenoid brake mounted on the end of the motor shaft, and this brake holds the motor shaft, to- 70

gether with the gripper jaws 10, from any further rotation in either direction. The disconnection of current also sets a solenoid brake 37, mounted on the other end of the hollow shaft 21, which also holds the hollow shaft 21 from turning. It will be seen that by this means the 5 advance end of the strip 1 is held rigidly in the elevated position shown in Figure 9. Meanwhile roller 3 is being carried along by the trolley 6 and is carrying with it a loop 38, of the strip, thus formed. This loop 38 will hereafter be called the looped end. The revolving of rotor of the motor 9 is synchronized with the drive motor of the mill in such a way that the strip 1 is carried away from the mill as fast as it 10 passes through the rolls, by the table rollers of the roller table 8 and the trolley 6. It will be seen however, that the trolley 6 need only move half the speed of the strip 1, since the strip 1 is now doubled. The primary purpose of this 15 part of the invention, namely the doubling of the strip, has now been accomplished as shown.

By referring to Figure 1 it will be seen that as the trolley 6 advances, heels 39 of the supporting arms 5 come in contact with swinging supports 40, mounted in pairs opposite each other on the roller table 8. These supports have two arms, a support arm 41 and a trigger arm 42, which are at right angles to each other. While one arm 42 is out over the table, parallel to the table rollers 44, the other arm 41 lies in a direction almost parallel to table girders 43 and out to one side of table rollers 44. This condition is shown in the right hand half of Figure 1. The heels 39 contact the trigger arms 42 out over the roller table 8 and as the trolley 6 continues its travel, carry the trigger arms 42 along with the heels 39. The arms 41 and 42 are supported on the top end of vertical shafts 45, which are free to rotate in cylinders 46. These cylinders 46, 40 which are fastened to the roller table girders 43, support the vertical shafts 45 and at the same time allow them to rotate. Stops are located in proper places in the cylinders 46 to limit the rotation of the swinging arms 41 and 42 to approximately 90°. As the heel 39 swings the arm 42 around, the other arm 41 is swinging in towards the loop 38, the top layer 47 of which is held in an elevated position above the lower layer 48, by means of the carrier roller 3. As the arms 41 swing in they travel in under the top layer 47 of the loop 38. This is brought about by the curved shape of the arms 41, the ends of which are curved downward to get in under the top layer 47. As the rotating action is continued the arms 41 come to rest out over the table and under the top layer 47 in approximately the same location as the other arm 42 was in. This condition is shown in left hand half of Figure 1. There being one of these supporting arms 41 on each side of the roller table 8, opposite each other, the top layer 47 of the loop 38 is supported stationary on these arms while the lower layer 48 advances over the power driven table rollers 44. As the trolley 6 continues its advance these arms 41 are 50 thrown into position successively until finally, when the trolley 6 arrives at the end of its advance, as shown in Figure 1a, the top layer 47 is supported from gripper jaws 10 to carrier roller 3 on these support arms 41. When the proper time arrives the trolley 6 reverses its direction and the carrier roller 3 contacts the arms 41 out over the roller table, reversing the swing of the arms 41 and 42 and kicking them back into their 55 60 65 70 75

original position, as shown in right hand half of Figure 1.

As the trolley 6 continues its travel from the position as shown in Figure 9, the tail end 49 of the strip 1 approaches the rolls of the mill 2. Closely after this tail end 49 has passed through the rolls, and the strip is free from the mill, this tail end 49 passes over a third trigger switch 50, as shown in Figure 16, right hand end. The resulting movement of the trigger switch 50 allows electric current to pass through the reversing control of the motor 16 setting it in reverse motion. This motion is passed through the sprocket wheels 17 and 19 and the chain 18 and solid shaft 20 to the cam 22 backing it off from the movable jaw 12. The pressure of the cam 22 now having been released from the movable jaw 12, the spring 24 coiled around it forces the movable jaw 12 to follow the cam 22 thus moving it away from the end of the strip 1 which it has been holding rigidly. This end of the top layer 47 which is now loose from the gripper jaws 10 is free to fall on to the end of the lower layer 48, below it, which has just passed through the mill 2 and over the trigger switch 50. This end which has just passed over the trigger switch 50, now passes over a fourth trigger switch 51 placed a very short distance from the switch 50. The releasing of this trigger switch 51 opens the circuit to the motor 16 which now stops and sets its solenoid brake holding solid shaft 20 and the cam 22 at the position shown at right hand end of Figure 16. The gripper jaws 10 are still up, because the solenoid brake 37, shown in Figure 11 mounted at end of hollow shaft 21, is still gripping the hollow shaft 21 and prevents it from turning. It does not release at the same time as the solenoid brake on motor 16 releases. The trolley 6 continues to advance, carrying with it the doubled strip trailing after it, until it nearly reaches the position as shown in Figure 1a.

Now referring also to Figures 12 and 13 in addition to Figure 1 it will be seen that at this point in the travel of the trolley 6, just before it reaches the end of its travel, two short manipulator rollers 52 and 53 are inserted between the top 47 and bottom layer 48 of the strip 1 at a point closely adjacent to the carrier roller 3. This operation is accomplished as follows: Rollers 52 and 53 are mounted on the ends of two short shafts 54 and 55. These two shafts are in turn mounted on the upper ends of two screws 56 and 57. Screw 56 passes down through a sleeve nut 58. On the upper end of this sleeve nut 58 is mounted, and keyed to it, a sprocket wheel 59. This sprocket is held in place, as to vertical movement, by two ribs of a housing 60; one rib above the sprocket 59 and one under it. In this same space is placed another sprocket 61 which is bored and threaded to fit the screw 57, and the two sprockets 59 and 61 are connected by a continuous chain 62. Thus, when one sprocket revolves the other is forced to revolve with it. On the lower end of the sleeve nut 58 is mounted, and keyed to it, a bevel gear 63. Since both sprocket 59 and bevel gear 63 are mounted on this sleeve 58, and both keyed to it, when one revolves the other is forced to revolve with it. Also, since the inside of the sleeve nut 58 is threaded to fit the screw 56, when the nut 58 is revolved this raises or lowers screw 56 according to the direction the nut is revolved. The bevel gear 63 meshes with a bevel pinion 64 which is connected by suitable coupling and shafts to a motor reduction unit 65. It will now be seen that when the motor reduction set revolves the pinion

64, the movement is transmitted through bevel gear 63, sleeve nut 58, sprockets 59 and 61, and chain 62, to the two screws 56 and 57. This movement either raises or lowers the two screws simultaneously according to the direction in which the motor revolves. The lower ends of screws 56 and 57 are formed into square shafts 66 and 67. These squared portions are inserted in correspondingly squared holes in two worm gear segments 68 and 69. These two segments are mounted in a space between two ribs of housing 60 in a similar manner to sprockets 59 and 61. Thus the vertical movement of the worm gear segments is prevented; but shafts 66 and 67 can raise and lower in segments 68 and 69, a sliding fit being provided. Worm gear segments 68 and 69 mesh with two worms 70 and 71. One worm is threaded with a right hand thread; the other with a left hand thread, and the two worms are mounted on the same shaft 72. This shaft is connected by suitable coupling to a motor gear reduction set 73. It will be seen that when the motor reduction set 73 revolves the shaft 72, and worms 70 and 71, that the movement is transmitted through worm gear segments 68 and 69 to square shafts 66 and 67 revolving these also. Due, however, to the right hand and left hand threading of worms these two shafts 66 and 67 are rotated in opposite directions. It will be seen now, by referring to Figure 12, that through the rotation of shafts 66 and 67, which are integral with screws 56 and 57, the short manipulator rollers 52 and 53 can be swung in from a position parallel with the table girders 43 to a position across the table and parallel with the rollers 44, as shown in Figure 12. When they operate thus they swing in between upper layer 47 and lower layer 48 of the strip 1; and while there, can be lowered or raised by the revolving of the sleeve nut 58 together with sprockets 59 and 61. The swinging in of the rollers 52 and 53 is timed by electrical switches or manual control to take place as the trolley 6 and carrier roller 3 are arriving at the end of their travel under a hammer 74.

The trolley 6 having continued its advance while the aforesaid operations were taking place, has now reached the end of its travel as shown at the left end of Figure 1. At this instant the table rollers 4, 44, and table rollers 77 are stopped by electric switches or manual control. Referring to Figure 1, left end, it will be seen that the roller 3 has now arrived directly under the hammer 74 and has reached the end of its forward travel. At this point a finger on some part of the trolley frame trips a switch 105 which reverses the trolley motor 9 and starts the trolley back towards the mill. Referring to Figure 13 it will be seen that the carrier roller 3 has already moved back a short distance, freeing the looped end 38 from the roller 3 and allowing it to sag down onto an anvil 75 underneath it. The control to the hammer 74 is now set in operation, either by an electrical switch, tripped by the trolley, or manually by an operator. Also at this time the motor reduction gear set 65 is put in motion, timed by electrical switches or manual control, and revolves in the proper direction to lower the screws 56 and 57, carrying with them manipulator rollers 52 and 53 to the position shown. This position is such that the carrier roller 3 can pass over the rollers 52 and 53. Referring to Figure 14 it will be seen that this has taken place. As soon as roller 3 is in this position the motor set 65 is started in the reverse direction, pushing manipulator rollers 52 and 53 up into position shown.

The hammer 74 has now descended and flattened out the looped end 38 and a pinch roller 76 is part way down in its travel. Referring to Figure 15 this shows the trolley 6 with the roller 3 as having moved back towards the mill still further. The hammer 74 has returned to its original position, pinch roller 76 has descended until it pinches the strip against the table roller 77 underneath it. The table rollers 4, 44, and 77 have again been started at the moment this contact took place. This action has forced the doubled and flattened loop end to move ahead as shown towards the rolls of a mill 78 ahead. The function of the pinch roller 76 is to cause the table roller 77 under it to move the doubled and flattened looped end ahead into the mill 78. As soon as this is accomplished the pinch roller 76 can be raised to its original position. Figure 16 shows these actions to have taken place. The doubled strip is now in the grip of the rolls of the rolling mill 78 and pinch roller 76 is again back to its original position. As the pinch roller 76 rose, motor set 65 was again put in motion forcing the manipulator rollers 52 and 53 up and carrying with them the top layer 47 of the strip 1. When the top layer 47 was elevated to the position shown in Figure 16 current was disconnected from the motor set 65 stopping it and holding the top layer 47 of the strip in position shown. This causes the two layers of strip 47 and 48 to be separated as shown, the opening decreasing from the rollers 52 and 53 to where the strip is gripped between the rolls of the mill 78. A spray nozzle 79 is placed on each side of the strip. These spray nozzles 79 are connected by suitable piping to storage tanks, pumps, and other necessary equipment to cause a spray of liquid or finely powdered material to be emitted from the spray nozzles 79. The nozzles are adjusted to such a position that the spray is blown into the opening between the top layer 47 and the lower layer 48 just as they are being forced together by the rolls of the mill 78. The valves which control the sprays are operated by suitable triggers placed over or under the strip so that the sprays are only blowing while there is a strip in the mill. The function of the liquid or powder used is to prevent the two layers of strip from sticking together so badly that separation necessary later in the cycle of operations would be difficult. When the tail end of the top layer 47 of the strip has passed over the manipulator rollers 52 and 53 they are lowered and moved to their original position alongside of the roller table 8, and ready to function when the next strip comes along. It will be seen that the trolley 6 and the roller 3 have successively kicked back the supporting arms 41 allowing the top layer 47 of the strip to fall on the lower layer 48; and has arrived at position 60 shown, near to its starting point. Gripper jaws 10 are still in the upper position so that the roller 3 can pass under them and resume its original starting position. The trolley 6 and roller 3 continue their travel until this position is reached. As the roller 3 arrives at that position it contacts a trigger switch 106 placed above it on the arm 27. This switch allows electrical current to flow to the motor 16 and release its solenoid brake and also to solenoid brake 37 which is thus released and allows the motor 16 to operate until the gripper jaws 10 are returned to their original position ready for the next strip. At this point the finger 34 on the hollow shaft 21 has again contacted the trigger of switch 33 mounted on arm 27 opening the current, thus stopping the

motor 9 and setting its brake and also solenoid brake 37. This operation completes the cycle of operating movements between the mills and all the equipment is ready for the next strip to come along. 5

Referring to Figure 4 the operations between the two mills 80 and 81 shown are identically the same as the foregoing description which covers the operations between the two first mentioned mills. The only exception is that four layers of strip pass through the outgoing mill 81 following hammer 82 in Figure 4. Referring to the left side of Figure 1, after the doubled strip has passed through the mill 78 the strip will be passed through one or more mills 105, shown in Figure 2 and will then pass to a shear 83 shown in Figure 3 where flattened looped end 38 will be sheared off. After a forward movement of strips the forward end will be manually opened on an opening table 84 following the shear 83 and then entered into a sticker opener 85 where the entire length of top layer 47 and lower layer 48 will be separated or opened. Strips 47 and 48 will now be coiled, if desired, or will pass into a continuous furnace 86 shown in Figure 3 for reheating; top layer 47 still laying on lower layer 48. After leaving reheating furnace 86, the reheated strips 47 and 48 will pass through one or more mills for further gauge reduction. It will then again upon leaving mill 80, shown in Figure 4, pass through the same operations described previously as taken place between first mentioned mills, shown in Figure 1. The only exception is that two layers of strips enter the first mill 80 shown in Figure 4 and are doubled into four layers, so that four layers of strip pass through the outgoing mill 81, following the hammer 82. The twice doubled strips (four layers thick) will now pass into one or more mills 87, shown in Figure 5 for gauge reduction. From mill 87 it will pass to shear 88 where flattened looped end will be sheared off. After some forward movement it will be manually opened for a short distance on opening table 89 following the shear 88 and passed into sticker opener 90, shown in Figure 6 where the entire length will be separated or opened into two layers, top layer 91 and lower layer 92, each of which will be composed of two layers. These will pass on to opening tables 93 and 94 where they will be manually opened and entered into the rolls of sticker opener 95 and 96. Having been thus opened there will be four separate strips 97, 98, 99, and 100. These will be coiled on reels 101, 102, 103, and 104, removed and banded ready for use. The material now will be a thin gauge. 55

What we claim is:—

1. In apparatus for doubling metal sheets, a roller table, a doubling roller mounted for movement over the table from end to end of the latter, and means operable, when the doubling roller is positioned at the sheet receiving end of the table, to grip the advance end of a sheet and move and hold the same across the path of movement of the roller toward the other end of the table, whereby said latter movement of the doubling roller will effect doubling of the sheet. 60

2. In apparatus for doubling metal sheets, a roller table, a doubling roller mounted for movement over the table from end to end of the latter, a frame pivotally mounted above the table at the sheet receiving end of the latter, cooperating fixed and movable gripping jaws carried by the frame, means for operating the movable jaw to grip the advance end of a sheet, means for 70

subsequently pivoting the frame to a position to dispose the advance end of the sheet across the path of movement of the doubling roller when the latter is positioned at the same end of the table as the pivoted frame, and means for subsequently moving the doubling roller toward the other end of the table to effect doubling of the sheet.

3. In apparatus for doubling metal sheets, a roller table, a doubling roller mounted for movement over the table from end to end of the latter, fixed spaced bearings supported above the table, a shaft rotatable in said bearings, a frame carried by said shaft, a device carried by the frame for gripping the advance end of a sheet to be doubled, means for operating said device into gripping relation to a sheet, means for subsequently rotating said shaft to move the frame and gripping device to a position to dispose the advance end of the sheet across the path of movement of the doubling roller when the latter is pivoted at the same end of the table as the pivoted frame, and means for subsequently moving the doubling roller toward the other end of the table to effect doubling of the sheet.

4. In apparatus for doubling metal sheets, a roller table, a doubling roller mounted for movement over the table from end to end of the latter, fixed spaced bearings supported above the table at the sheet receiving end of the latter, a tubular shaft rotatable in said bearings, a frame carried by the shaft, a device carried by the frame for gripping the advance end of a sheet to be doubled, a solid shaft rotatable in the tubular shaft, means for rotating the solid shaft, a cam on the solid shaft extending through an opening in the tubular shaft and operable during initial rotation of the solid shaft to cause the gripping device to clamp the advance end of a sheet to be doubled, and during subsequent rotation of the solid shaft to rotate the tubular shaft to move the frame to a position to dispose the advance end of the sheet across the path of movement of the doubling roller when the latter is at the same end of the table as said shafts, and means for subsequently moving the doubling roller toward the other end of the table to effect doubling of the sheet.

5. In apparatus for doubling metal sheets, a roller table, a track structure above the table, a carriage movable on said track structure, a doubling roller on the carriage, means at the sheet receiving end of the table for positioning and anchoring the advance end of a metal sheet across the path of movement of the doubling roller when the latter is in its initial position, and means for moving the carriage and doubling roller over the table to effect doubling of the sheet and for returning the carriage and doubling roller to initial position after the doubling operation is complete.

6. In apparatus for doubling metal sheets, a roller table, a track structure above the table, a carriage movable on said track structure, a doubling roller on the carriage, a device positioned at one end of the table including a pivoted sheet gripper, means for pivoting and anchored sheet gripper, means for pivoting and anchoring the gripper to and in a position to dis-

pose the advance end of a metal sheet in the path of movement of the doubling roller when the latter is in its initial position, means for moving the carriage and doubling roller toward the opposite end of the table to effect doubling of the sheet, means at the opposite end of the table for delivering the doubled sheet to a mill, means for returning the carriage and doubling roller to initial position, and means for returning the pivoted sheet gripper to position to receive the next sheet to be doubled.

7. In apparatus for doubling metal sheets, a roller table, a track structure above the table, a carriage movable on said track structure, a doubling roller on the carriage, spaced arms rigidly depending from the track structure at the sheet receiving end of the table, a frame pivotally mounted between the arms, fixed and movable gripping jaws carried by the frame, cam means for operating the movable jaw to grip the advance end of a metal sheet between the jaws, means for pivoting the frame to a position to dispose the advance end of a sheet across the path of movement of the doubling roller when the latter is in its initial position, means for moving the carriage and doubling roller over the table to effect doubling of the sheet, means for returning the carriage and doubling roller to initial position, and means for returning the pivoted frame and its gripping jaws to position to receive the next sheet to be doubled.

8. In apparatus for doubling metal sheets, a roller table, mechanism for doubling a sheet over the table, arms mounted at spaced points along the table for pivotal movement to and from a position to support the upper layer of the sheet in spaced relation to the lower layer during the doubling operation, means operated by movement of the doubling mechanism to successively move said arms to supporting position as the doubling operation progresses, and means included in the doubling mechanism successively engaging and moving the arms from layer supporting position during movement of the doubling mechanism occurring after the doubling operation is completed.

9. In apparatus for doubling metal sheets, a roller table, mechanism for doubling a sheet over the table, and devices located at spaced points along the table successively operated by the doubling mechanism during its doubling movement to a position to support the upper layer of the sheet in spaced relation to the lower layer and to a position to release said layer to the influence of gravity during the opposite movement of the doubling mechanism.

10. In apparatus for doubling metal sheets, mechanism for doubling a sheet over the table and devices mounted at spaced points along the table successively operated during doubling movement of the mechanism to a position to support the upper layer of the sheet in spaced relation to the lower layer and to a position to release said layer to the influence of gravity after the doubling operation is completed.
